COMBINATION HANDLE AND CLIP FOR CONTAINERS

Roy C. Potts, Takoma Park, Md.

Application December 20, 1946, Serial No. 717,570

6 Claims. (Cl. 229—52)

Fig. 5 is a side view thereof, Fig. 6 is a side view of the top of the top cover, and Fig. 7 is a side view of the top of the bottom cover.

This invention relates to containers, particularly to fibreboard containers of the type adapted for shipment of such commodities as eggs, fruits and vegetables, and has for its principal object the provision of means for securing the parts of such containers together in the desired relationship, but which means are readily removable to permit folding of the container to a flat condition for empty shipment.

A further object of the invention is to provide fastening means of the type indicated which may be utilized without the use of any tools whatever, either in applying or removing the fasteners, and which are moreover adapted to perform certain other functions such as the provision of convenient handles on the outer walls of the containers, without any of the usual complications required in multiple use devices of this general kind.

A still further object of the invention is to devise fastening means of the type described which are very simply formed of low-cost material, and which may therefore be supplied at an absolute minimum of cost. An ancillary object of the invention is to provide fasteners whose use does not complicate the container structure as such; more particularly, the fasteners of my invention require only simple slots in certain of the panel members of the containers, which slots can readily be incorporated during the manufacture of the box, without expensive die-cutting operations; for example, the slots required may readily be formed during the operation of the conventional rotary fibreboard cutting and slotting machines.

The use of fasteners of the type herein described and claimed is more fully illustrated in connection with certain improved forms of containers forming the subject matter of my application Serial No. 717,569, now abandoned, filed concurrently herewith; the description of the present case, therefor, is limited almost entirely to the structure of the clips or fasteners themselves, and reference is made to the above-mentioned application for the details of the use of such fasteners in connection with particular forms of containers.

My invention will best be understood by reference to the following description of certain preferred embodiments thereof, taken in connection with the accompanying drawings, in which:

Fig. 1 is a perspective view of a portion of a two-ply end wall of a fibreboard container illustrating the use of one form of fastener.

Fig. 2 is a plan view of the same fastener.

Fig. 3 is a side view thereof.

Fig. 4 is a plan view of a second form of fastener.

Fig. 5 is a side view thereof.
Fig. 6 is a plan view of a modified form of fastener.

Fig. 7 is a side view thereof,
Fig. 8 is a side view of the form of fastener

Fig. 8 is a side view of the form of fastener shown in Figs. 6 and 7, but further modified for use as a handle,

Fig. 9 is a plan view of a still further modification of a fastener.

10 Fig. 10 is a side view thereof.
Fig. 11 is a side view of a further slight medi-

Fig. 11 is a side view of a further slight modification of the form of Figs. 9 and 10.

Fig. 12 is a plan view of a further form of the invention.

Fig. 13 is a side view thereof.
Fig. 14 is a view similar to Fig. 13 but of a fastener additionally modified.

Fig. 15 is a plan view of another form of fastener.

Fig. 16 is a side view thereof, and Figs. 17 to 19 are views thereof.

Figs. 17 to 19 are perspective views of further modifications.

25 Referring now to Fig. 1 of the drawings, there is shown a broken away portion of one two-ply end of a fibreboard container of the type more fully described in my concurrent application mentioned above. The two plies are designated 10 and 12, and each has an elongated slot therein, designated broadly as 14. In order to secure the two panels together against movement either 30 away from one another or in a sliding fashion, a fastener 16 is provided, and preferably formed of a single piece of such material as stiff wire. As shown in Figs. 1 to 3, fastener 16 comprises a connecting leg 18 and two depending legs 20 and

35 22, these parts being substantially coplanar and defining a U-shaped or stirrup-shaped portion adapted to engage the outer surface of panel 10 when inserted through slot 14. Each of legs 20 and 22 turns in a direction perpendicular to the plane of the stirrup portion to provide slot-penetrating portions 24 and 26, and then each turns outwardly to form a loop (28 and 30 respectively), the loops being coplanar and approximately parallel to the plane of the stirrup portion. As 40 shown best in Fig. 3, the normal or rest plane of the loops 28 and 30 is slightly inclined to the plane of the stirrup, to provide a tension grip upon the panels 10 and 12 when the clip or fastener is inserted.

50 If it is desired to cover over the loops 28 and 30 on the inside of the container, as well as to seal the exposed portions of slot 26, a strip of adhesively coated paper 32 (Fig. 1) may be pasted over the projected area of the parts to be covered.

55 If desired to permit ready re-use of the con-

33. If desired to permit ready re-use of the container and facilitate insertion and removal of the fastener, such strip may be adhesively se-

cured only in the area designated 34, being normally held in covering position by gravity or pressure exerted by the contents, but readily swingable to a position giving access to the fastener and slot.

It will be readily understood that, if the fastener 16 is inserted as shown in Fig. 1, and if panel 10 constitutes the outer panel of a container, then the leg 18 constitutes a convenient handle for the container, a duplicate fastener at the other end of the container providing a convenient means for handling the filled case. In other words, mere insertion of the fasteners as a matter of container assembly may simultaneously provide outside handle members. The springy nature of the wire of which the fasteners are preferably fabricated enables the leg portion 18 to be grasped and pulled somewhat away from the outer surface of the container for a firm finger grip, but, as described hereinafter, it is also feasible to provide a permanent outwardly-deflected location of leg 18 where the handle feature is particularly to be emphasized, without in any way lessening the value of the member as a fastener.

The fastener 16 described above is constituted by portions of substantial area or projected area which lie respectively in slightly spaced planes approximately parallel to one another, although before use, as mentioned, such planes may be slightly inclined to one another in the interest of a firm grip. Connecting these portions are short members adapted to pass through the elements to be secured together. Thus, the contact between the gripping portions (e. g., the portion made up of legs 18, 20 and 22 and the portion made up of loops 28 and 30) and the surfaces to be secured is distributed over a relatively extensive area of such surfaces, which eliminates all danger of tearing or distorting the material of the panels, and increases the effectiveness of the fastening action. Further, the fastener is formed of a single piece of material, such as wire, whose terminal areas are turned closely against adjacent non-terminal portions to provide a structure which is free from sharp edges or corners which might cause injury to the user, to the container or to the contents of the case.

The principles of the invention as outlined above may, of course, be satisfied by designs which are specifically different. Certain of these modifications are described below, but it is to be understood that the description of specific forms herein is not to be construed to exclude other equivalent forms which come within the scope of such principles as defined in the claims appended hereto.

Figs. 4 and 5 show a form of the invention in which the stirrup is formed by three legs 40, 42 and 44, the latter two turning rearwardly as at 46 (Fig. 5), thence upwardly as at 48 and thence toward one another as at 50 and 52, terminating closely adjacent one another. In this embodiment, the fastener comprises in effect two U-shaped or stirrup-shaped portions in approximately parallel planes, the legs of each being joined by the panel-penetrating portions 46. Here again, the clamping areas are extensively distributed over the faces of the container material, and the fastener has all the features described above in connection with Figs. 1 to 3.

In the embodiment shown in Figs. 6 and 7, the fastener comprises of central leg 54 and depending legs 56 and 58 forming therewith a stirrup portion; each of legs 56 and 58 turns rear-

wardly as best shown in Fig. 7 at 60, and thence the two legs turn toward one another as at 62 and 64 of Fig. 6 to form closed loops lying within the profile of the stirrup portion. As best shown in the modified form of Fig. 8, each of the legs 56 and 58 may be bent approximately midway of its length so that the central leg 54 will be somewhat spaced from the outer wall of a carton to facilitate gripping by the fingers where the device is to be used as a handle.

The modification shown in Figs. 9 to 11 is very similar to that shown in Figs. 6 to 8 except that the portions 62' and 64' corresponding to portions 62 and 64 of Fig. 6, are turned outwardly rather than toward one another, so that the loops lie outside the profile of the stirrup portion formed by the legs 54', 56' and 58'. In this embodiment, therefore, the distance between the terminal loops is somewhat greater than the form in Fig. 6, providing a better purchase upon the interior panel of a carton, but requiring a slightly greater area of contact on the inside of such carton.

In the forms shown in Figs. 12 to 14, the handle-forming stirrup comprises a central leg 70, depending legs 72 and 74 which turn rearwardly to pass through the carton slots as at 76 of Fig. 13, thence upwardly approximately parallel to the portions 72 and 74, and then reversely downward as at 78 and 80 of Fig. 12. The ends of the piece are then turned toward one another as at 82, 84, terminating closely adjacent one another as best shown in Fig. 12. It will be seen that in this form of the invention there are in effect two stirrup portions 70—74 and 78—80, and that these two portions lie in planes slightly inclined to one another for contact with the carton wall forming panels. As indicated in Fig. 14, the portions 72 and 74 may be bent between their ends to form the outstanding handle grip mentioned above.

The form of Figs. 15 and 16 is closely similar to that just described, the outer stirrup comprising legs 86, 88 and 90. In this modification, however, the side legs 78' and 80' of the second stirrup-portion lie within the profile formed by members 86, 88 and 90.

Fig. 17 is a perspective illustration of a somewhat modified form of combined handle and fastener 100, shown as used in combination with a multi-ply wall composed of panels 102 and 104. Both of the plies of the wall structure are slotted or perforated as at 106, and through this slot is passed the stirrup-shaped handle portion of the handle, comprising a horizontal portion 108 and depending leg portions 110 and 112. Leg 112 is bent rearwardly as at 114 to pass through the slot 106, thence upwardly as at 116 and thence reversely downward as at 118 and then again upwardly as at 120. The parts 116, 118 and 120 lie in a common plane, and the length of portion 114 is so chosen that parts 116 to 120 closely engage the opposite surface of the wall member. The portion 120 terminates in a forwardly disposed loop 122 adapted to pass into or through the slot 106. Hence, the fastener or handle leg engages the material defining the top edge of slot 106 at a plurality of spaced points, increasing the resistance to tearing out of such material. The inherent resilience of the springy wire from which the handle is constructed enables the device to be readily inserted into the slot, yet provides for a firm grip upon the opposite surfaces of the wall. Furthermore, the dual engagement at each side normally restricts removal of the fastener by either upward pull or downward pres-

sure thereon. Intentional removal, however, is achieved by pressing outwardly on the panel material at the lower edge of slot 106 to disengage loops 122 from the edges of the slot, whereupon the fastener may be slid out of engagement just as are the simpler forms earlier described herein.

Inasmuch as the parts associated with leg 110 are bent into a mirror image of the parts associated with leg 112, it is deemed unnecessary to describe these similar parts in detail.

Fig. 18 shows a modification of the fastener 100, generally designated in that figure by numeral 130. The depending legs 132 and 134 are of the same shape as described in connection with Fig. 17, except that the ultimate end of each leg is turned toward the end of the other, as indicated at 136 and 138, the terminals 140 and 142 lying just beneath the material defining the upper edge of slot 106, and in the plane of one or the other of the wall elements. The illustration of this form shows the handle applied to a single-ply wall member 144 having a usual form of closure flap 146 hingedly connected thereto at its upper edge. Thus, any usual form of fibre-board container may be converted into a handled container merely by providing appropriate slots in the end wall panels and top closure flaps. As so used, of course, the flaps may be turned either inwardly or outwardly with respect to the container to enable insertion of the handle member through the registering slots.

In order to provide increased strength and resistance to tearing of panel 144, particularly where the container material is corrugated board, rather than fiber-board, a re-inforcing strip 147 of cardboard, chipboard, fiberboard or the like may be inserted as indicated, with one edge in the fold connecting panel 144 and closure flap 146, the lower edge passing along the top edge of slot 106. Such a strip greatly increases the durability of the container wall, by increasing the area over which the stress applied by handle 130 is distributed, and hence increases the resistance to tearing of the material along the top edge of the slot.

A further modification is shown in Fig. 19, the depending legs 150 and 152 of the fastener passing rearwardly through the slot 106 as at 154, thence upwardly as at 156, diagonally downward as at 158 to a point below the level of slot 106, thence again upwardly as at 160, and terminating in a short forwardly bent portion 162 adapted to pass into or through slot 106. The latter portion provides the spaced point of contact with the top edge of the slot as described above. It will be understood that the opposite leg is formed in a similar (reversely symmetrical) fashion. As indicated at 164, the connecting portion between legs 150 and 152, which forms the finger grip of the handle, may be spaced away from the wall panel, as by bending the legs 150 and 152 intermediate their ends, to facilitate positive engagement of the fingers with such handle portion. This construction may also be applied to the combined handle and fasteners of Figs. 17 and 18, and is of particular value where the handle portion does not extend above the top edge of the container. In the latter circumstance, as indicated in Fig. 18, such a spaced-away handle portion would be unnecessary.

It will be seen that I have satisfied the objects of my invention by various forms of fastener having certain essential features in common, but it will be understood that other variations and

modifications are possible, and I do not intend to restrict my invention to the particular forms herein described, except insofar as required by the language of the claims.

5 I claim:

1. A unitary preformed wire handle and fastener member adapted for use in handling and carrying fiber board containers comprising: a transverse handle-grip segment, a downwardly extending leg at each end of the segment, the end portions of said legs lying in a single plane, a work penetrating member at the end of each leg, said work penetrating members being formed at right angles to the plane of said legs and lying in a single plane, an upturned segment at the end of each said work penetrating member looped within a plane substantially parallel to the plane of said legs, the end portions of said looped, upturned segment being turned at right angles toward the plane of said legs and lying in a plane coincidental with the plane of said work penetrating members, said end portions of said looped, upturned segments being themselves looped.

2. A device as set forth in claim 1 in which the looped end portions of said looped, upturned segments lie in the plane of the work penetrating members.

3. A device as set forth in claim 1 in which all portions of the looped, upturned segments lie within a projection of the transverse handle-grip segment and its legs except a portion intermediate the upturned loops and the free ends thereof.

4. A device as set forth in claim 1 in which the extreme end portions of each of said looped upturned segments lie in a plane coincidental with the plane of the work penetrating members, said end portions being in abutting, linear alignment with each other.

5. In combination, a container having a wall perforated by an elongated slot and a unitary preformed wire handle and fastener member of the type set forth in claim 1 and having the handle-grip segment and its legs on the outside of the wall, the upturned loop segments on the inside of the wall and the work penetrating members passing through said slot.

6. In combination, a container having a wall perforated by an elongated slot and a unitary preformed wire handle and fastener member of the type set forth in claim 4 and having the handle-grip segment and its legs on the outside of the wall, the upturned loop segments on the inside of the wall, the work penetrating members passing through said slot and the extreme end portions of the upturned loop segments lying within and bearing on the walls of said slot.

ROY C. POTTS.
